INVENTOR

Frank S. Bunker

BY

Carl S. Crawford
ATTORNEY

UNITED STATES PATENT OFFICE.

FRANK S. BUNKER, OF SPOKANE, WASHINGTON.

AUTO JACK.

Application filed August 16, 1921, Serial No. 492,717. Renewed September 15, 1924.

To all whom it may concern:

Be it known that I, FRANK S. BUNKER, a citizen of the United States, residing at Spokane, in the county of Spokane and State of Washington, have invented new and useful Improvements in Auto Jacks, of which the following is a specification.

This invention relates to improvements in auto jacks and has to do more particularly with an improved wheeled jack which is especially designed for use in garages and service stations in serving the public.

My invention includes lifting mechanism preferably of the pressure type, which is mounted upon an improved support, one of the novel features of which is that the support has three points of engagement with the floor or other supporting surface.

My improved support is specifically carried by bearing wheels forming two of such points of support, said support also including a frame journaled on or carried by said wheels and having an apex portion forming the remaining point of support.

In the foregoing type of auto jack, it is a feature of my invention to mount the lifting mechanism preferably rigidly on the frame, the rigid mounting being of such a character as slightly to yield sufficiently to prevent telescoping portions of the lifting mechanism from binding, when under the heavier loads.

It is also a feature of this invention to provide a novel form of handle whereby the portable jack may be rolled into and out of operative positions, means being provided whereby the pressure necessary to operate the lifting mechanism may be conveyed to the latter, or exhausted therefrom, through the handle, whereby the handle may perform the dual function of a means for manipulating the jack and also causing its lifting mechanism to be energized.

A further object is to provide the improved lifting mechanism with a mechanically extensible jack stem whereby the latter may be extensively or contractively adjusted to increase the range of operation of a given sized jack.

My invention has many other features and objects which will be more fully described in connection with the accompanying drawings and which will be more par-

particularized out in and by the appended claims.

In the drawings:—

Figure 1 is a view in side elevation of one form of my improved auto jack.

Figure 2 is a view on line 2—2 of Figure 3, of the carriage portion of the jack, parts being in section and parts being in elevation.

Figure 3 is a plan view thereof.

Figure 4 is an enlarged sectional view of the manipulating end of the handle.

Figure 5 is a sectional view on line 5—5 of Figure 4.

Like characters of reference designate similar parts throughout the different figures of the drawings.

Reference will first be made to the carriage portion of the jack, such portion including bearing wheels 1, on which the jack is advanced. A substantially triangular frame 2 is journaled on an axle 3 which is fixed to the wheels 1. Said frame has a bight or base portion 4, parallel portions 5 and portions 6 which converge to an apex 7. At the apex 7, the frame is provided with parallel portions 8 to which a handle is attached, as will later appear. It will thus be seen that the wheels 1 constitute two points of support and the apex 7 of the frame the remaining point of support.

A saddle 9, preferably of U-shape form, has its limbs 10 secured to the frame portions 5, preferably rigidly, as by means of bolts 11. While the saddle 9 is of metal, and substantially rigid, its thickness or gauge is greatly reduced with respect to the frame and therefore when the saddle is not under load, it is to all intents and purposes a rigid saddle. However, when the saddle is under heavy load, there is a sufficient yield to permit the lifting mechanism to "set" itself to support the load. This is one of the features of this invention, the function and advantage of which will be more apparent when the lifting mechanism has been described.

My improved lifting mechanism comprises a pressure cylinder 12 which is preferably provided with an integral upper head 13 having a suitable flange 14. A lower head 15 having a suitable flange 16 is secured to the cylinder 12 by means such as

bolts 17. The head 15 rests upon the saddle 9 and the bolts 17 extend through the head 15 and saddle 9 thereby rigidly planting the cylindrical structure to the saddle. The head 15 is provided with an annular groove 18 into which the lower edge of the cylinder 12 seats. Said head is also provided with a pressure intake port 19 which opens to the bottom of cylinder 12 and which is connected at 20 with a pressure supply tube 21. A piston 22 is disposed in cylinder 12 and is equipped with suitable packing as shown. Said piston is provided with an abutment 23 adapted to engage a packing 24, mounted upon the head 15, whereby a descending movement of the piston will be arrested. Said piston is provided with a sleeve 25 which projects through head 13 and has slidable engagement therewith at 26, whereby the piston is guided. The bore 27 of said sleeve terminates at 28 and is provided on its upper end with a ratchet pawl projection 29, extending into the bore. A jack stem or bar 30 is loosely fitted in said sleeve and when in a contracted adjustment, said bar rests on the bottom 28. The upper end of said bar has a jack seat 31 provided with protuberances 32, adapted to grip bottom portions of the auto to be elevated. One side of said bar 30 is provided with teeth 33, for engagement with pawl 29. As shown in Figure 2, this extensible jack element is in a contracted adjustment. In Figure 1, the extensible jack is in a partially extended adjustment. By means of this feature, I am enabled to extend the range of this jack very materially without unduly enlarging the same. Thus I am able to get under a very low car and hoist the same, or I am able to move the jack under a relatively high car and lift the latter. In any position which the extensible feature may occupy, it is in rigid structural engagement with the piston sleeve and no movable parts of a fastening nature are necessary.

The desirability of having a very slightly yielding mounting for the lifting mechanism will now be clear, this being especially so when the mechanism is in an extended operative position.

Attention will next be directed to my improved handle and to the various functions which it performs.

The improved handle is designated at 34 the same being in the form of a hollow pipe of the general configuration shown in Figure 1. Thus it will be obvious that the operator walking upright can grasp the pipe by the handle end 35 and readily advance or retract the jack to and from desired positions. The carriage end 36 of the pipe terminates in a connection 37 having an eye 38 extending between the frame members 8. A bolt 39 secures the handle in place and by reason of the engagement at 40, the con-

nection constitutes one which is substantially rigid. The tube 21 is united with a nipple 41 and communicates with 37 thereby conveying the pressure medium to the bottom of cylinder 12.

To the outer extremity of the handle end 35 is attached a fitting 42 into which a valved air service pipe connection 43 projects. The valve stem is indicated at 44. Said fitting 42 is provided with a closure 45 having a valve seat projection 46. A valve closure 47 seats against the end of said projection and is provided with a stem 48 extending through said projection and having a button 49 on the outer end thereof. A spring 50 normally holds the closure 47 seated. Key grooves 51 may serve as channels to exhaust the air from the handle.

Now when the jack is in position and ready to be operated to lift a portion of an auto, the air service hose is applied to 43. Air under pressure is conveyed through the handle 34 and tube 21 to the bottom of piston 22 and the latter will be raised to the desired extent. The non-return valve 44, in part 43 will prevent escape of air and will hold the jack in its actuated position. When it is desired to lower the auto, pressure is applied, manually, to the button 49, in the direction of the arrow shown in Figure 4, and the air may be exhausted from the handle and the cylinder either as rapidly or as gently as desired.

It will be noted from Figures 1 and 2 that the frame of the carriage portion is at an inclination to the horizontal when in a position of rest although the bottom of the saddle is substantially horizontal and the cylinder is substantially vertical. It will also be noted that by this arrangement, the apex portion 7 will engage the floor and firmly retain the jack in any position to which it has been advanced.

It is believed that the invention will be clearly understood from the foregoing description and I do not wish to be limited except for such limitations as the claims may import.

I claim:

1. An auto jack including a lifting mechanism, a three point support therefor comprising an axle and a pair of supporting wheels on said axle forming two points of support, a substantially triangular frame having its base end journalled on said axle and free from engagement with the floor, and said frame having an apex end for engagement with the floor and forming the remaining point of support, and a handle fixed to said apex end, whereby elevation of said handle will lift said apex end off from the floor and shift the weight onto said wheels.

2. An auto jack including lifting mechanism and a three point support therefor in-

- cluding a frame, and a slightly yieldable saddle rigidly hung on said frame and rigidly secured to said mechanism whereby the latter may slightly shift its position under 5 the heavier loads.
3. An auto jack comprising a wheeled frame, a cylinder mounted on said frame and having a lifting piston, a hollow handle pipe secured to said frame to advance said 10 jack, an air pressure tube leading from the frame end of said handle pipe and connected with said cylinder, an air intake valve on the handle end of said pipe for connection with an air service hose to actuate said piston, 15 and an air exhaust valve on the handle end of said pipe for exhausting air from said cylinder to permit restoring movement of said piston.
4. An auto jack comprising a cylinder, a 20 piston in said cylinder having a piston sleeve extending through and in guided engagement with one head of said cylinder.
- having a fixed tooth, and a jack bar extension extensible in said sleeve and having teeth for engagement with said sleeve tooth 25 to rigidly hold said bar in extensible positions.
5. An auto jack substantially as described, having a hollow handle provided with a non-return valve for connection with an air 30 service hose, and said handle having an exhaust valve for exhausting the air from said jack.
6. An auto jack comprising a frame having laterally spaced members, a slight yieldable U-shaped saddle having its ends rigidly secured to said members and its bight spanning the space between said members below the anchored ends thereof, and lifting mechanism rigidly secured to the bight 35 40 of said saddle.

In testimony that I claim the foregoing as my own, I hereby affix my signature.

FRANK S. BUNKER.
